UNITED STATES PATENT OFFICE.

ROSS McFARLAND, OF PORTLAND, OREGON.

NAIL FILE.

Application filed March 7, 1928. Serial No. 259,641.

My invention relates to nail files in which the handle is provided with a separate clip.

The objects of my invention are to provide a nail file in which the clip and file can be manufactured and tempered separately; in which the clip can be adjusted to any depth of pocket; which can be used as a cigar cutter; and which eliminates the disadvantages of a clip formed as an integral part of the file handle.

Other objects and advantages are to be found in the construction and arrangement of parts as will be described in the specification and particularly pointed out in the appended claims.

I attain these objects with the mechanism, illustrated in the accompanying drawings, in which:

Fig. I is a plan view of a file with a slide-
able clip.

Fig. II is a side view of Fig. I.

Fig. III is a bottom view of the handle in
Fig. I.

Fig. IV is a section through Fig. I along
the line IV—IV.

Fig. V is a modification of the cigar cutting edge shown in Fig. I.

Fig. VI shows the clip firmly attached to
the handle of the nail file.

Similar numerals refer to similar parts
throughout the several views.

A nail file, besides serving as a manicuring tool, could be used as an opener for cigarette packages, an opener for envelopes, a knot opener, a scraper of paint or labels from glass surfaces, and other like purposes, providing it were always handy and within reach; this demands that a nail file should always be carried in a person's pocket, and should have a clip to prevent the loss from the pocket. Nail files with clips stamped out as an integral part of the handle have been manufactured heretofore, but this entailed a large amount of breakage in the manufacture and use of the file. Furthermore, file steel and spring steel have a different composition and require different methods of tempering, so that integral manufacture of file and clip did not prove practical; further, such a clip did not permit adjustment to the depth of the pocket.

To obviate these disadvantages, and also to add a new function to my nail file, namely that of a cigar cutter, I take a file 1 of tool steel and cut a longitudinal slot 2 in the handle 3, said slot 2 terminating in a round hole

4 with a sharp edge 5 near the top of the handle 3. I then take a clip 6 which is manufactured of spring steel, and provided with wings 7 and 8 which not only encircle the edges of the handle 3 with a sliding fit, but one of the wings 7 is bent over to enter the slot 2 and to press against the edge of the slot 2 with a sliding fit, thus preventing the clip 6 from slipping beyond the limits of the slot 2 and also to impart to the clip 6 in its movement in longitudinal direction a strong guiding effect. The other wing 8 not only covers the slot 2, but overlaps and rests firmly on the first mentioned wing 7 to make the accidental disengagement of the latter from the slot more difficult. That edge of the clip 6 which is directed toward the round hole 4 carries a slanting cutting edge 9 with the point either to one side as in Fig. V, or preferably in the center as in Fig. I whereby the point 10 pierces the tip of the cigar and holds the latter firmly in place as the cutting edges sever the cigar tip.

Where a sliding clip is not desired, the same may be welded, soldered or riveted firmly in place as shown in Fig. VI. The advantages to be found in the manufacture of different kinds of steel, and the separate tempering can thereby still be obtained.

Having thus described my invention, it will be seen that my objects have been accomplished, and, though I have shown the preferred form of construction, I reserve to myself the right to make minor changes, providing I do not contravene the spirit and principle of my invention.

I claim:

1. In a nail file, the combination of a flat handle, a longitudinal slot in said handle, said slot terminating in a round hole near the top of the handle, a spring steel clip, wings on the clip encircling the handle slidably, one of said wings entering the slot, the other wing overlapping the slot and pressing against the first-named wing, and a cigar-cutting edge projecting from the clip toward the round hole in the handle.

2. A nail file having a flat handle portion, a longitudinal slot in the handle portion, with a clip of spring steel separately manufactured and tempered, wings integral with the clip, said wings encircling the handle portion slidably, one of said wings entering the longitudinal slot, the other wing overlapping the slot and pressing against the first-mentioned wing.

3. A nail file having a flat handle portion, a longitudinal slot in the handle portion, said slot terminating in a round hole with a sharpened edge near the top of the handle portion, with a clip of spring steel, wings integral with the clip, said wings encircling the handle portion slidably, one of said wings entering the longitudinal slot, the other wing overlapping the slot and pressing against the first-mentioned wing, said clip carrying a cigar cutting edge in shearing relation with the round hole.
4. A nail file having a flat handle portion, a longitudinal slot in the handle portion,

said slot terminating in a round hole with a 15 sharpened edge near the top of the handle portion, with a clip having wings to encircle said handle portion slidably, one of said wings entering the slot, the other wing overlapping the slot and pressing against the 20 first mentioned wing, and a cigar cutting edge projecting from the clip in shearing relation with the flat handle and terminating in a sharp point at the center line of the longitudinal slot.

25

In testimony whereof I affix my signature.

ROSS McFARLAND.
